UNITED STATES PATENT OFFICE.

CHARLES J. SAGEBRECHT, OF BROOKLYN, NEW YORK, ASSIGNOR TO INTERSTATE ELECTRIC NOVELTY CO., OF NEW YORK, N. Y., A CORPORATION OF NEW YORK.

PORTRABLE ELECTRIC FLASH-LIGHT.

1,122,424.

Specification of Letters Patent.

Patented Dec. 29, 1914.

Application filed May 21, 1914. Serial No. 889,922.

To all whom it may concern:

Be it known that I, CHARLES J. SAGEBRECHT, a citizen of the United States, and a resident of Brooklyn, in the county of 5 Kings and State of New York, have invented certain new and useful Improvements in Portable Electric Flash-Lights, of which the following is a specification.

The invention pertains more particularly 10 to portable electric lights of a character adapted, owing to size and compactness, of being carried in the pocket of the user.

Considerable difficulty has heretofore existed in some classes of pocket flash lights in 15 preventing the moving around of the battery within the metal casing and the accidental making of the circuit through the lamp, battery and casing due to such shifting of the battery, the shifting of the battery frequently carrying its terminal into 20 contact with the circuit closer. The result of this has been that the batteries have been unnecessarily consumed and sometimes have been pronounced worthless, whereas in fact 25 they have been consumed while the lamp was in the pocket of the user and without his knowledge.

The object of the present invention is to 30 provide a compact flash light adapted to receive a battery of ordinary construction and to avoid the contingency of the circuit being made by an accidental shifting of the battery in the case.

The invention will be fully understood 35 from the detailed description hereinafter presented, reference being had to the accompanying drawings, in which:

Figure 1 is a side elevation of a pocket flash light or electric lamp embodying my 40 invention; Fig. 2 is an elevation of the same with the two halves of the inclosing casing shown in their open position; Fig. 3 is a transverse section, on an enlarged scale, through the same on the dotted line 3—3 of 45 Fig. 1; Fig. 4 is a vertical section, also on an enlarged scale, through the upper portion of the same on the dotted line 4—4 of Fig. 1; Fig. 5 is an enlarged view of a portion of one-half section of the same, corresponding with the left hand portion of Fig. 50 2, showing the circuit closer as having been moved to its circuit closing position from its normal position illustrated in Fig. 2, and Fig. 6 is a detached sectional view about 55 on a line 6—6 of Fig. 1, showing the latch

for latching the two half sections of the outer casing in closed position.

In the drawings 10 designates an exterior metal casing of rectangular general outline but having rounded edge portions, said casing being composed of two shallow half sections 11, 12 connected together at one edge by the hinge 13 and at their opposite meeting edges being equipped with latch members comprising a leaf spring 14 riveted at its upper end, as at 15, to the half section 11 and provided at its lower portion with a latch member 16 and thumb-piece 17, said thumb-piece being extended through a slot 18 formed in the section 11 and said latch member 16 being simply an extension of the spring 14 and containing an opening to snap over a stud 19 formed by indenting the metal of the section 12 inwardly for the purpose of interlocking with said latch-member 16 when the two half sections of the casing are closed together, see Fig. 6. There is no special novelty in the means for locking the two half sections of the casing together.

In the middle portion of the upper end of the half section 12 of the casing 10 is secured a reflector 19^a and the other half section of the casing at its upper middle portion is recessed, as at 20, to fit around said reflector. Within the reflector 19^a is secured the electric lamp bulb 21 whose threaded socket engages said reflector and also enters a bracket plate 22 which is somewhat of right-angular formation and fastened directly to the inner wall of the half section 12 by solder or otherwise, the exterior casing and lamp being by means of said bracket 22 placed in electrical connection. Upon the vertical member of the bracket 22 is secured a bar 23 of non-conducting material, and upon the outer end of this bar is secured by eyelets or rivets 24, two substantially corresponding plates 25, 26 of right-angular formation having outer parallel transversely extending members constituting between them a jaw 27. The non-conducting material or bar 23 prevents electrical connection of the plates 25, 26 with the bracket 22.

The battery, numbered 28, is of usual construction and seated within the half section 12 of the exterior casing, and said battery 28 has its long inwardly bending terminal 29 below and in contact with the lower

end of the socket for the lamp 21, and its vertical short terminal 30 extended upwardly into the jaw 27 formed by the plates 25, 26, as will be understood on reference to Figs. 2, 3 and 5. The battery 28 is seated upon a right-angular flange 31 which is soldered to the half section 12. Fig. 2 shows the electric lamp with the casing thereof opened outwardly, but otherwise illustrates the parts of the lamp in their normal position with the circuit closer spring 32 in its upper position free of the jaw 27 and the plates by which said jaw is formed. The circuit closer spring 32 lies within the outer vertical portion of the half section 12, and it is adapted to have a vertical movement under the influence of manual pressure applied to a buttonhead 33 connected therewith and having its shank within a vertical slot 34 in the half section 12. The lower end of the spring 32 is slotted, as at 35 (Fig. 5), and held by a loose rivet 36 whose shank is within said slot 35. The slot 34 in the half section 12 and the slot 35 in the lower end of the spring 32 permit the user of the flash light to slide the spring 32 downwardly or upwardly to the extent permitted by said slots. The upper end of the spring 32 is bent downwardly and inwardly and then upwardly and rearwardly into the form approximately of the letter V, as at 37. When the upper bent end of the spring 32 is in its upper position shown in Fig. 2 there will be no circuit through the battery and lamp, the circuit being broken at the space between the upper bent end of said spring 32 and the facing portion of the plate 25 and battery terminal 30. When it is desired to complete the circuit through the battery and lamp the user will, by pressure applied to the push-button 33, cause the spring 32 to slide downwardly, and this will result in the spring at its upper bent end engaging the plate 25 and completing the circuit through the battery and lamp.

In order to assure an adequate contact of the upper bent end of the spring 32 with the plate 25 when said spring is pushed downwardly and to avoid said bent end from normally standing too close to said plate 25 and to the battery terminal 30, I form a stud 38 on the inner surface of the half section 12 behind the spring 32 and form a recess or loop 39 in said spring so that when the spring is in its upper position said recess or loop may pass upon and engage the stud 38 and by its spring tension lie close against the surface of the section 12 and also so that when the spring 32 is slid downwardly, the stud 38 will act to wedge the upper bent end of the spring inwardly toward and against the plate 25, this latter action being illustrated in Fig. 5. The plates 25, 26 hold the battery terminal 30 and so position said terminal that any slight shifting of the bat-

tery within the casing will not result in said terminal being moved into engagement with the circuit closer spring 32. The plates 25, 26 may be bent to some extent to adapt them to the small variations that exist in the position of the terminal 30 with respect to the battery.

It is believed the invention will be fully understood from the foregoing description, and that further explanation is not required. It may be mentioned however that the plate 26 may be nonconducting or even, with some disadvantage, omitted, since the plate 25 extends at right angles to and transversely of the terminal 30 and above the battery 28 and is, at the proper time, engaged by the bent end of the spring circuit closer 32 to complete the circuit through said battery terminal 30. The engagement of the plate 25 with the terminal 30 and the fact that said plate extends transversely of and above the battery permits said plate to aid in holding the battery in place.

What I claim as my invention and desire to secure by Letters Patent, is:

1. A portable electric light comprising a casing in two hinged together substantially corresponding longitudinal sections having latching means at their free edges, a battery in one of said sections having the usual two terminals, an electric lamp socketed in the end of the same section and in electrical engagement with one of said terminals, a jaw secured within and insulated from said section and receiving between its members the other of said terminals, and a circuit closer carried by said section and having an upper end to engage the adjacent conducting member of said jaw when in one position and stand clear thereof when in its other position.

2. A portable electric light comprising a metal casing in two hinged together substantially corresponding sections having latching means at their free edges, a battery in one of said sections having the usual two terminals, a bracket secured within and near the upper end of the same section, a reflector held at the end of said section, an electric lamp held by said bracket with its bulb within said reflector and its contact in engagement with one of said terminals, a jaw insulated from and secured to said bracket and receiving between its members the other of said terminals, and a slideable circuit closer carried by said section and having an inwardly extended upper end to engage the adjacent conducting member of said jaw when in one position and stand clear thereof when in its other position.

3. A portable electric light comprising a casing in two hinged together substantially corresponding longitudinal sections having latching means at their free edges, a battery

- in one of said sections having the usual two terminals, an electric lamp socketed in the end of the same section and in electrical engagement with one of said terminals, a jaw 5 secured within and insulated from said section and receiving between its members the other of said terminals, and a slideable circuit closer carried by said section and having an inwardly extended upper end to 10 engage the adjacent conducting member of said jaw when in one position and stand clear thereof when in its other position, said circuit closer being of spring metal having an exposed head connected therewith for its 15 manual operation and also a recess in its
- outer face, and said section having an inwardly projecting stud to enter said recess when the closer is in its inoperative position and serve as a wedge to force the upper end of said closer into engagement with 20 said conducting jaw member when the closer is moved to its operative position.

Signed at New York city, in the county of New York and State of New York, this 19th day of May, A. D. 1914.

CHARLES J. SAGEBRECHT.
